UNITED STATES PATENT OFFICE.

JOE E. McDOWELL, OF FORT WORTH, TEXAS.

PNEUMATIC STAGE PUMP.

Application filed June 17, 1921. Serial No. 478,254.

To all whom it may concern:

Be it known that I, JOE E. McDOWELL, a citizen of the United States of America, residing at Fort Worth, in the county of Tarrant and State of Texas, have invented certain new and useful Improvements in Pneumatic Stage Pumps, of which the following is a specification.

My invention relates to pumps and more particularly to pneumatic pumps; and the object is to provide pumps which will be highly efficient in pumping oil or water by dividing the work to be done into sections so that the water or oil may be elevated by successive stages with mechanism for operating the pumping elements at each stage independently of any other section or stage, the object being to use a minimum of power. A further object is to provide continuous operation of the pumping elements by preventing the binding or sticking of the floats or valves. A further object is to provide means for automatically opening the air or gas valves when a section is filled with oil or water and for automatically shutting off the operating element whether gas or air when a section is empty. A further object is the use of air or gas as a piston operating on the surface of the liquid for forcing the liquid into the next higher section and not allowing the air or gas to become mixed with the liquid and so preventing the air or gas from emulsifying the liquid or oil. One of the advantages of this invention is that a head of oil may be prevented from rising in the well above a predetermined level. This feature makes the invention especially applicable and valuable for use in oil wells. Other objects and advantages will be fully explained in the following description and the invention will be more particularly pointed out in the claims.

Reference is had to the accompanying drawings which form a part of this application.

Fig. 1 is a vertical section of a well casing and the cylindrical supporting frame. Fig. 2 is an enlarged detail of the pumping elements. Fig. 3 is a horizontal section, taken on the line 3-3 of Fig. 2. Fig. 4 is a top plan view of an intake and outlet

valve for a section or stage of the pump. Fig. 5 is a horizontal section, taken on the line 5-5 of Fig. 2. 55

Similar characters of reference are used to indicate the same parts throughout the several views.

The drawings show a well casing 1 of ordinary type. Any number of units may be provided for use in the well casing. At the lower end or bottom of the pump, a perforated pipe 2 projects into the producing sands. An intake valve 3 opens and closes the end of the pipe 2 which projects into the cylindrical frame 4. The oil or other liquid will be retained in the chamber 4 and will rise up about the pumping elements. The liquid will rise up through the valve 6 into chamber 7 and passes on into the storage pipe 8 and also into a discharge pipe 9. In the first instance, the liquid rises up into these parts without any pumping action. The pipes 8 and 9 are connected to the unit member 4 and also to the unit member 10. The liquid will force the valve 11 to close the passage 12 and at the same time open the valve 13, allowing the gas or air to enter chamber 14, forcing the liquid downward and out through valve 15 and into pipe 9 and up against the valve 16 and raises this valve. This actuates the lever 17 which is connected with and actuates the three-way valve 16. This action will bring passage 18 into communication with the gas supply pipe 19. This will let gas or air pass through the valve 16 and out the passage 12 because the passage 12 is of sufficient area to cover the passage 20 even after the valve 16 has been turned by the lever 17 and passage 21 will be turned away from opening 22. 85

The gas or air will force the oil or other liquid in chambers 14 and 8 downwardly and such liquid will pass out through valve 6 and up the pipe 9 past valve 15 to the next section above which may be twenty or forty feet more or less. In this operation, the valve 11 will be forced downwardly and the gas or air will be cut off from passing through valve 13. In the position shown in Fig. 2, the valve 16 would let air from the chamber 14 and 8 pass out through passage 20 and then out passage 21 and then out 100

through opening 22 to the atmosphere. This lets the air out of the way of oil that would rise up from the bottom into chambers 8 and 14.

5 When the liquid is forced up pipe 9 and past valve 15, as above described, the liquid passes to the next unit which is separated from the unit above described by the valve 15 and partition 27. The air or gas is forced 10 down the supply pipe 29 and out through pipe 19 or through valve 13 for the above described operations.

When the oil passes valve 15 into chamber 28, it is in the second unit. The oil or other 15 liquid will pass on through the chamber 28 and through the passage 30 and cylindrical chamber 24, past valve 25 into chamber 26. This operation is kept until the chamber 26 is full of liquid, and the pipe or chamber 32 is also filled. The valve 15 and the partition 20 27 form the support for the second unit. The liquid passes up pipe 33 at the same time. The next operation is to force the liquid out of chambers 32 and 26 up through 25 the chamber or pipe 33. The upward pressure of liquid in chamber 32 closes the valve 34. This will open valve 35 and let air or gas in on the surface of the liquid in chamber 32 and at the same time closes valve 15 30 and brings valve 16 to the position shown in Fig. 2. The pressure of air or gas on the surface of the liquid in chambers 32 and 26 will force the liquid up pipe 33 and through the valve seat 36. This will let gas or air 35 pass through pipe 37 down through the valve in casing 38 and open valve 34 and close valve 35. This will give full force of the gas or air on the surface of the liquid in chambers 32 and 26, and so drive the liquid up pipe 33 into the next unit.

Auxiliary shut-offs are provided in each 45 unit to aid the operations above described under certain contingencies. If there is not sufficient liquid in the lower chamber to fill the chamber above and start the valve 34 to working, then, when the chamber is emptied, the float 39 will follow the surface of the liquid down and close valve 40 in the chamber 7. This will stop the flow of liquid 50 through valve 6, but the pressure on the valve 40 will force the same down to the bottom of the valve chamber 6, drawing the float 39 down and forcing the lever 41 down and opening a valve incasing 42 so that the air or gas pressure will escape to the atmosphere. In this operation the spring 43 is overcome. When the pressure is thus relieved, the liquid standing in chamber 26, chamber 32, and pipe or chamber 33 will 55 come through valve 15 and close this valve. The parts will then stand as in Fig. 2. The float 39 is protected and guided by a shield 44. When the parts come to normal position as shown in Fig. 2, the spring 43 60 will restore the lever 41 to normal position

and close the passage through opening 45. The spring 46, lever 47, casing 48, valve 49, opening 50, valve 25, float 51, and shield 52 are all similar in construction and operation to the construction and operation of the spring 43 and co-operating parts above described.

What I claim, is,—

1. A pneumatic stage pump comprising a plurality of units, a gas or air supplying pipe common to all the units, each unit having a chamber provided with an intake valve and an air outlet for escape of air from said chamber while liquid is coming in, a liquid discharge pipe, a gas or air starting valve adapted to communicate with said supply pipe and to be automatically opened by the liquid coming in said chamber, a main gas or air valve operatively connected to said supply pipe and to be automatically opened by liquid forced out of said chamber up said discharge pipe whereby gas or air is supplied to said chamber for closing said starting valve and for forcing liquid out of said discharge pipe to the next unit above. 90

2. A pneumatic stage pump comprising a plurality of units, a gas or air supply pipe common to all the units, each unit having a chamber provided with an intake valve and an air outlet for escape of air from said chamber while liquid is coming in, a discharge pipe, a float valve to be automatically closed by incoming liquid, a gas or air starting valve operatively connected with said float valve to be automatically opened by incoming liquid actuating said float valve, said starting valve communicating with said supply pipe, a main gas or air valve operatively connected to said supply pipe and to be automatically opened by liquid forced out of said chamber whereby gas or air is supplied to said chamber for closing said starting valve and for forcing liquid out of said discharge pipe to the next unit above. 95

3. A pneumatic stage pump comprising a plurality of units, a gas or air supply pipe common to all the units, each unit having a chamber provided with an intake valve and an air outlet for escape of air from said chamber while liquid is coming in, a discharge pipe, a float valve to be automatically closed by incoming liquid, a gas or air starting valve operatively connected with said float valve to be automatically opened by incoming liquid actuating said float valve, said starting valve communicating with said supply pipe, a three-way valve operatively connected with said supply pipe and adapted to close said air outlet and simultaneously let in a supply of gas or air, a float valve operatively connected to said three-way valve and adapted to actuate the same when said float valve is actuated by liquid forced from said chamber whereby gas or air is supplied 110 115 120 125 130

to said chamber for closing said starting valve and for forcing liquid out of said discharge pipe to the next unit above.

4. A pneumatic stage pump comprising a plurality of units, a gas or air supply pipe common to all the units, each unit having a chamber provided with an intake valve and an air outlet for escape of air from said chamber while liquid is coming in, a discharge pipe, a float valve to be automatically closed by incoming liquid, a gas or air starting valve operatively connected with said float valve to be automatically opened by incoming liquid actuating said float valve, said starting valve communicating with said supply pipe, a three-way valve operatively

connected with said supply pipe and adapted to close said air outlet and simultaneously let in a supply of gas or air, a float valve operatively connected to said three-way valve and adapted to actuate the same when said float valve is actuated by liquid forced from said chamber whereby gas or air is supplied to said chamber for closing said starting valve and for forcing liquid out of said discharge pipe to the next unit above, and auxiliary valves in each chamber for starting operations when there is no liquid in the chamber of a unit.

In testimony whereof, I set my hand, this first day of June, 1921.

JOE E. McDOWELL.
